Primary Examiner — David G Muller*(74) Attorney, Agent, or Firm* — Muncy, Geissler, Olds & Lowe, P.C.(57) **CLAIM**

I claim the ornamental design for a dismantling tool, as shown and described.

DESCRIPTION

FIG. 1 is a top, front, right perspective view of a dismantling tool showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 a bottom, rear, left perspective view.

The broken lines in the drawings illustrate portions of the dismantling tool which form no part of the claimed design. The dot-dashed line in the figures defines the boundary of claimed design and forms no part of the claimed design.
